COMBINED TOOTHPICK AND GUM MASSAGER

Hjalmar Otto Sandin, 24 Kungsgatan,
111 35 Stockholm, Sweden

Filed Dec. 17, 1973, Ser. No. 425,526

Term of patent 14 years

Int. Cl. D28—03

U.S. Cl. D86—10 D

FIG. 1

FIG. 3

FIG. 1 is a perspective view of a combined toothpick and gum massager showing my new design;

FIG. 2 is a perspective view in the opposite direction; and

FIG. 3 is a side elevational view.

I claim:

The ornamental design for a combined toothpick and gum massager, as shown and described.
